UNITED STATES PATENT OFFICE.

WILLIS H. DWIGHT, OF LEMARS, IOWA.

MEANS FOR ATTACHING TOOTH MEMBERS.

SPECIFICATION forming part of Letters Patent No. 710,444, dated October 7, 1902.

Application filed December 27, 1900. Serial No. 41,281. (No model.)

To all whom it may concern:

Be it known that I, WILLIS H. DWIGHT, a citizen of the United States, residing at Lemars, in the county of Plymouth and State 5 of Iowa, have invented a new and useful Means for Attaching Tooth Members, of which the following is a specification.

This invention relates to means for applying members of teeth to the latter, but particularly pertains to means for securing crowns or facings to artificial dentures, the means for attaching either a crown or facing being substantially similar; and it consists in the construction and arrangement of the 15 several parts, which will be more fully hereinafter described and claimed.

In the drawings, Figure 1 is a transverse vertical section of a crown, showing the flared socket and a yielding enlargement on the 20 post to fit in the said socket. Fig. 2 is a detail elevation of the post and enlargement.

Similar numerals of reference are employed to indicate corresponding parts in the views.

The improved construction is shown in use 25 with a crown, to which it is particularly adapted; but in some instances it may be desired to employ the same in connection with a facing, and for the latter purpose the proportions and dimensions will be varied. The 30 crown 1 is formed with a frusto-conical seat or recess 2, in which is fitted and secured a similarly-shaped socket 3, of tubular form and closed at one end. The post 4 is provided with a terminal enlargement 5, also of frusto- 35 conical form and constructed of spring metal, the free edge of the said enlargement being formed with notches 6 to permit compression of the enlargement for introduction into the

socket. Though the said yielding enlargement will be sufficient under all circumstances to hold a post in place, it is preferred that the socket be supplied with a quantity of cement, as shown, to prevent the post from having a rotary movement, the notches in the edge of the enlargement providing a locking means when indented in the cement. The cement filling will be placed in the socket either by flowing or otherwise, and it will be seen that when the enlargement 5 is pushed into the cement filling a contraction of the 45 free edge will be resisted, and hence said enlargement will be prevented from being withdrawn from the socket. The socket 3 will be formed of suitable metal and will provide a strong wall for receiving the enlargement 50 5. The post 4 will be provided with screw-threads; but in some instances the threads may be dispensed with. On the post a cupped band attachment 7 is shown and will be used at times; but it will be obvious that in some 55 instances this may be removed.

Having thus described the invention, what is claimed as new is—

A tooth member having an undercut socket, and a post having a terminal frusto-conical 65 enlargement of a resilient nature so that it can be compressed and sprung into said socket.

In testimony that I claim the foregoing as my own I have hereto affixed my signature in 70 the presence of two witnesses.

WILLIS H. DWIGHT.
